(57) **CLAIM**

The ornamental design for a door stop/door hanger, as shown and described.

DESCRIPTION

FIG. 1 is a perspective view of a door stop/door hanger showing our new design;

FIG. 2 is a top plan view thereof;

FIG. 3 is a rear elevational view thereof;

FIG. 4 is a front elevational view thereof;

FIG. 5 is a right side elevational view thereof, the left side elevational view being a mirror image;

FIG. 6 is a bottom plan view thereof; and,

FIG. 7 is a front elevational view of the door stop/door hanger of FIG. 1 with different broken line indicia.

The broken lines shown in the drawings are for the purpose of illustrating unclaimed portions of the door stop/door hanger and form no part of the claimed design.

The dotted-line showing in the drawings illustrates environmental matter or material reduction recesses and forms no part of the claimed design.
